F. W. SCHNEEMAN,
PEN AND PENCIL HOLDER,
APPLICATION FILED FEB 8, 1911.

1,078,001

Patented Nov. 11, 1913.

UNITED STATES PATENT OFFICE.

FREDERICK W. SCHNEEMAN, OF NEW YORK, N. Y.

PEN AND PENCIL HOLDER.

1,078,001.

Specification of Letters Patent. Patented Nov. 11, 1913.

Application filed February 8, 1911. Serial No. 607,248.

To all whom it may concern:

Be it known that I, FREDERICK W. SCHNEEMAN, a citizen of the United States, residing at New York city, in the county of New York and State of New York, have invented new and useful Improvements in Pen and Pencil Holders, of which the following is specification.

This invention relates to pen and pencil holders and the like and has for its object to provide a simple device of this character particularly adapted to be stamped integrally from sheet material.

Another object is to provide a holder having an efficient point protector for pencils of various sizes.

Other objects and advantages will be apparent from the following description and from the drawings, in which,

20 Figure 1 is a front view of the device with a pencil therein, Fig. 2 is a side view thereof, Fig. 3 is a plan of the blank, Fig. 4 is a vertical section through the complete device, Fig. 5 is a top view of the device.

25 Referring to the drawings, there is shown a holder comprising a body plate or blank 10, formed with the integral clasp arms 11 on each side in opposed position, the plate being extended therebeneath a proper distance and provided with the integral point-receiving cup or pocket 12. The arms 11 are simply lateral continuations of the plate 10 bent in closely against the plate 10 at their bases as at 13, then being turned outwardly and curved inward to form a pencil-receiving space 14, their extremities being curved backwardly as at 15 to form pencil receiving portions adapted to be separated readily by pressure of a pencil inwardly therebetween.

40 The cup 12 comprises an extension from the lower end of the plate as at 16 in Fig. 3. The left lower corner of the plate is cut off diagonally on a line intersecting the longitudinal axis of the plate at its lower edge, and the extension 16 forms a segment of a circle having the point of said intersection as its center. The part 16 is bent inward on the line from that point where the edge of the plate 10 intersects the upper edge of the 45 extension, and curved until the lower edge of the extension rests against the opposite diagonal edge of the plate, forming a cone-like pocket. Pencil buffers 17 are struck inward from the portion 16 in the form of 50 arcuate loops, arranged to engage the tapered portion of the pencil just above the lead, to

prevent the lead from striking the sides of the pocket and breaking. To form the buffers, the segment is provided with pairs of approximately radial slits equally spaced from the point of the pocket, and the material between the slits of each pair is pressed inwardly in arcuate form, the metal being stretched thereby.

Above the arms 11 two small semi-circular apertures are formed as at 18, having closely spaced parallel chords, and receiving slidably therethrough the curved end portion 19 of a pin 20, the latter forming an eye revolvably engaged around the portion of material between the apertures 18. The pin extends longitudinally of the plate 10, its free end being pointed, and inwardly of which it is releasably confined by a tongue 21 pressed from the body of the plate as shown. The pin 21 is adapted for engagement with a coat, vest or other article of apparel for support of the holder.

In use, the device being secured upon the person of the wearer as described, a pencil so may be engaged therewith by simply presenting its point in the pocket 12 and pressing its intermediate portion laterally between the arms 11. Its disengagement involves the reverse operation.

It will be seen from the foregoing that an extremely simply manufactured device is provided in and out of which pencils and pens may be put and taken with a minimum effort and expenditure of time, and which will be efficient in the retention and protection of pencils disposed therein.

What is claimed is:

1. As an improved article of manufacture, a sheet metal blank for an integral pencil clip and point protector to be attached to apparel, comprising an elongated body portion having oppositely extended arms adapted to be bent forwardly to form a pencil holding means, the body having at one end spaced from the arms a lateral extension in the form of the segment of a disk having its center on the medial line of the body portion, the outer radial edge thereof forming an end edge of the blank and being adapted to be bent inwardly over the blank with said outer edge abutting the edge portion of the blank opposite the base of the extension to form a conical pocket, a plurality of pairs of slits being formed in the extension, the material between the slits of each pair extending radially of the center of the segment.

2
and being adapted to be pressed upwardly in the form of a bow and to form point fenders and pencil supports within the pocket.

2. A device of the class described, comprising an elongated body of sheet metal having integral spring arms formed at opposite sides and shaped to clasp a pencil, an integral extension at one side of the body at one end, bent inwardly thereover to form a conical pocket, the extension having pairs of slits therein and the material between the slits of each pair being bowed inwardly to

form pencil supports and extending in the mean direction of respective elements of the conic surface of the pocket and being uniformly spaced from the apex thereof, and support means for the device. ¹⁵

In testimony whereof I have hereunto set my hand in presence of two subscribing witnesses.

FREDERICK W. SCHNEEMAN.
